UNITED STATES PATENT OFFICE

EDWIN E. HOBBS, OF INDEPENDENCE, KANSAS

RADIO APPARATUS

Application filed February 4, 1928. Serial No. 251,793.

My invention relates to improvements in radio apparatus, and refers particularly to means for eliminating static in radio apparatus.

5 One object of my invention is the provision of static eliminating means adapted to be connected between the antenna and the input terminal of the radio receiving set and in the ground lead to the set.

10 Another object of my invention is the provision of means for eliminating static which will operate perfectly under all conditions and which will be of simple, inexpensive and durable construction to insure a practical and 15 highly desirable invention of this character.

With the objects stated in view, my invention consists of static preventing or eliminating means for radio apparatus embodying novel features of construction, combination 20 and arrangement of parts for service, substantially as described and claimed and as shown in the accompanying drawings, in which:

Figure 1 represents a side elevation of a 25 complete radio apparatus constructed in accordance with and embodying my invention.

Figure 2 represents a horizontal sectional view of the antenna of my invention.

Figure 3 represents a vertical central sectional view of said antenna.

Figure 4 represents a vertical central sectional view of the static eliminating unit of my invention.

Figure 5 represents a vertical central sectional view of the grounding unit of my invention.

Figure 6 represents a top plan view of the said ground element, and

Figure 7 represents a view of the apparatus 40 operatively connected to a receiving set.

In carrying my invention into effect I employ a tubular post of metal 1, which is of the desired and proper height and is braced by inclined guy wires or braces 2, which are connected at their upper ends 3, to the insulated ring 4, and are anchored at their lower ends 5, and upon the top of said post or tubular column is secured the antenna, which consists of a two part drum or casting 6-6¹, in the top of which is secured the

sleeve 7, with which is connected the segmentally or radially arranged arms 8, which lead out from the drum or casing and having the extended ends 9, which form the receiving means of the antenna.

The construction of the antenna is most clearly shown in Figures 2 and 3 and the lead wire 10 is connected to the plug 11 secured in the top or upper end of the post, and said lead wire passes down in the post and through the insulated opening 12, to the casing 13, the lead or conducting wire having formed thereon the coil 14, which is bare or free of insulation and said coil is immersed in a chemical composition, and I have found 55 from experience that the best results are obtained by using a composition of calcinated water, ammonia, paraffine oil, alum and rosin.

The structure described comprising the coil, the casing and the composition forms 70 the static eliminator, one of the essential features of my invention, and the lead wire has its outer end 15, passing from the eliminator to the set 15', and this portion of the wire may lead directly to the set, as shown in Figure 7, or may be bridged at 16, to the ground wire 17, leading to the ground unit or element, which consists of the metal casing 17', having its open end fitting in the box or closure 18, and said box is partially filled with 75 a composition of tar, cement, soil or clay, glass, sand, and the bottom, sides and top of the said box are made of any suitable material.

From the foregoing description taken in 85 connection with the drawings the operation of my invention will be readily understood, and it will be evident that the current enters the lead in wires of the antenna to the conducting wire and passes through the coil to the set and from the set through the wire to the ground as usual in all radio receiving apparatus, and the static is eliminated by the coil and the mineral in the casing forming the eliminator.

The eliminator consisting of the casing, the bare coil and the chemical charge forms a 90 most important feature of my invention in its relation to the other parts of my invention, and it will be apparent that my apparatus

tus can be easily and cheaply constructed and will operate in an efficient and practical manner for the purpose intended.

I claim:

- 5 1. In static eliminator, the combination of a support, an antenna associated therewith, an insulated conducting wire leading from said antenna, a bare coil forming a part of said insulated conducting wire, a casing enclosing said coil, a chemical composition filling said casing and surrounding said coil, an insulated portion of said conducting wire leading from said casing to a set, a ground element composed of a closed metal casing, insulating means therefor, a filling in said casing and surrounding box, and a wire leading to said casing from a set.
- 10 2. In radio apparatus, the combination with an antenna and receiving set, of a static preventing means disposed adapted to be connected between the antenna and the input to said set, and consisting of a casing containing a suitable liquid, a member immersed in the liquid in said container and consisting of a metal conductor whose surface has a portion exposed to said liquid and which conductor is connected in circuit between the antenna and receiving set, said portion being formed with a coil.
- 15 30 In testimony whereof I hereunto affix my signature.

EDWIN E. HOBBS.
